UNITED STATES PATENT OFFICE.

RALPH L. QUASS, OF NEW YORK, N. Y., ASSIGNOR TO WESTERN ELECTRIC COMPANY,
OF NEW YORK, N. Y., A CORPORATION OF ILLINOIS.

TELEPHONE SYSTEM.

1,156,626.

Specification of Letters Patent. Patented Oct. 12, 1915.

Application filed May 1, 1914. Serial No. 835,749.

To all whom it may concern:

Be it known that I, RALPH L. QUASS, a citizen of the United States, residing at New York, in the county of Bronx and State of New York, have invented a certain new and useful Improvement in Telephone Systems, of which the following is a full, clear, concise, and exact description.

This invention relates to telephone systems, and more particularly to systems of the central energy type having the ringing current automatically applied to the called line upon connecting the link conductors with the line conductors.

It is the object of this invention to improve systems of this character and to provide a system in which the usual "click" in the calling subscriber's ear, resulting from the closing through of the talking circuit upon the removal of ringing current from the line, is practically eliminated.

In accordance with a feature of this invention, means are provided at the central office whereby when ringing current is removed from the line the talking circuit is closed through very slowly, thereby practically eliminating the click in the receiver of the calling subscriber.

This invention is illustrated in the accompanying drawing in which all apparatus is shown in its normal and unactuated condition.

There is shown in the drawing a telephone system containing one embodiment of this invention and comprising the usual subscribers' stations A and B and a cord circuit C located at a central office for interconnecting the subscribers' stations. It is believed that this invention will be fully understood from a description of the operation of the system shown in the drawing, and it will be so described. Supposing subscriber A wishes to converse with subscriber B, A removes his receiver from the switch hook, thereby completing a circuit from the live pole of battery 5 through the winding of line relay 6, normally closed contact 7 of cut-off relay 8, line wires 9 and 10 and the other normally closed contact 11 of relay 8 to ground. Current in this path actuates the line relay 6 completing a circuit for the line signal 12. The operator, observing the line signal 12 inserts her answering plug in the jack indicated by the signal 12, and thereby completes a circuit from the live

pole of battery 13 through supervisory signal 14, normally closed contact 15 of relay 16, winding of relay 17, sleeve strand 18 of the cord circuit, sleeve contact 19 of the answering jack and the winding of cut-off relay 8 to ground. Current in this path actuates the cut-off relay 8, which severs the circuit of the line relay 6, effacing the line signal 12, and actuates the relay 17 connecting the operator's telephone set across talking strands 20 and 21 of the cord circuit. The insertion of the answering plug also completes a circuit from one pole of battery 25 through the winding of relay 26, over conductor 27, ring contacts 28 and 29 of the answering plug and jack, line wires 9 and 10, tip contacts 30 and 31 of the answering jack and plug, conductor 32 to the other pole of battery 25. Current in this path actuates relay 26, placing a low resistance shunt 33 about supervisory signal 14 and preventing its operation. The operator now asks the desired number of the calling subscriber. Finding the desired number to be that of subscriber B, the operator touches the tip of the calling plug to the sleeve of a jack corresponding to B's line to determine the idle or busy condition thereof. If the line tests idle, the calling plug is inserted in the jack completing a circuit from the live pole of battery 40, through supervisory signal 41, winding of relay 16, over conductor 42, sleeve contacts 43 and 44 of the calling plug and the jack and through the winding of cut-off relay 45 to ground. Current in this path actuates cut-off relay 45 cutting line relay 46 from the line conductors 47 and 48, operates the supervisory signal 41, and actuates the relay 16, disconnecting the operator's telephone set from the talking strands 20 and 21 of the cord circuit. Actuation of relay 16 also completes a circuit from the live pole of battery 49 through the winding of relay 50, normally closed contacts 51 of relay 52, 53 of relay 54 and 55 of relay 56, and normally open contact 57 (now closed) of relay 16 to ground. Current in this path actuates relay 50, connecting a source of ringing current 60 to the line through relay 54. Relay 54 is marginal and will not operate when in series with the usual ringer and condenser at the subscriber's station, but will operate when the ringer and condenser are shunted by low resistance.

The path for the ringing current through

the called subscriber's ringer is from 60 through winding of relay 54 over conductor 61, normally open contact 62 (now closed) of relay 50, ring contacts 63 and 64 of the calling plug and the jack, line wire 47, condenser 65, ringer 66, line wire 48, tip contacts 67 and 68 of the jack and calling plug, and normally open contact 69 (now closed) of relay 50 to ground. It will be observed that there is provided in this cord circuit a condenser 70 of small capacity which is shunted about the normally closed contact 71 of relay 50 and is connected to the talking strand 20 through normally closed contact 72 of relay 56 and conductor 73. From the point 74, the ringing current finds a second path through condenser 70, normally closed contact 72 of relay 56, conductors 73 and 20 and through winding 75 of repeating coil 76 to ground. The condenser 70 is of very low capacity so that there is only a small portion of the ringing current through the winding 75 of the repeating coil. This current is, however, sufficient to cause a tone to be repeated back to the calling subscriber, thereby making known to him that the called subscriber is being signaled. It will furthermore be observed that this tone to the calling subscriber does not depend upon the condition of the called subscriber's line or substation apparatus, and is, therefore, capable of being maintained constant so that the calling subscriber may at all times readily distinguish this tone from any other which may be placed upon the line from time to time. The normally closed contact 76 of the relay 50 may be shunted by a condenser 77 of about the same capacity as the condenser 70 so that when the cord circuit is arranged for ringing on party lines and ringing over the other line the calling subscriber may receive the tone.

The called subscriber upon removing his receiver from the switch hook, closes a path 45 of low resistance for the ringing current, thereby permitting a greater flow of current through the relay 54. Relay 54 is thereby actuated, opening the normal shunt about relay 52, and permitting relay 52 to be actuated by current from battery 49, lock itself up through its normally open contact 78 (now closed) and short circuit relay 50 which releases and removes ringing current from the line. Actuation of relay 52 also 50 closes a circuit for relay 56, which in operating locks itself up through its normally open contact 79 (now closed), releases relay 52 and closes its normally open contact 80, completing the talking circuit between subscribers A and B. Relay 56 is made slow 55 acting so that when it is energized contact 80 is closed very slowly, thereby eliminating the usual click in the receiver of the calling subscriber. When this contact 80 is closed, supervisory relay 85 is actuated by current

from battery 25 over the talking strands of the cord circuit and the line wires and through the winding of relay 85. Actuation of relay 85 effaces the supervisory signal 41.

Upon finishing the conversation, subscribers A and B restore their respective receivers to the switch hooks, thereby opening the circuits at their respective stations for current from battery 25. Supervisory relays 26 and 85 are thereupon deenergized, permitting the supervisory signals 14 and 41 to be operated. The operator thereupon removes the plugs from the jacks and all apparatus returns to its normal position.

While in this description various batteries have been referred to, it is to be understood that a common battery may be substituted for all of these and such is the usual practice. At the central office has been provided a key 86 by means of which the operator may at any time throw her telephone set across the talking strands of the cord circuit and supervise the established connection between the two subscribers.

What is claimed is:

1. A telephone system comprising telephone lines terminating at a central office, normally open link conductors thereat for connecting said lines in pairs, means associated with said link conductors for automatically applying ringing current to the called line upon connecting said link conductors therewith, means for automatically removing the ringing current from the called line, and means associated with said link conductors for slowly closing said normally open link conductors after the removal of the ringing current.

2. A telephone system comprising telephone lines terminating at a central office, normally open link conductors thereat for connecting said lines in pairs, means associated with said link conductors for automatically applying ringing current to the called line upon connecting said link conductors therewith, means for automatically removing the ringing current from the called line, and a slow acting relay associated with said link conductors and actuated after the ringing current is removed from the line for closing said normally open link conductors.

3. A telephone system comprising telephone lines terminating in a central office, link conductors thereat for connecting said lines in pairs, at least one of said conductors being normally open, means associated with said link conductors for automatically applying ringing current to the called line upon connection of said link conductor therewith, means for automatically removing the ringing current from the called line, and means associated with said link conductors and actuated after removal of the ringing current for closing said normally open link conductor.

4. A telephone system comprising telephone lines terminating in a central office, link conductors thereat for connecting said lines in pairs, at least one of said conductors being normally open, means associated with said link conductors for automatically applying ringing current to the called line upon connection of said link conductor therewith, a relay for automatically removing the ringing current from the called line, and an electromagnetic relay associated with said link conductor and energized after removal of the ringing current for closing said normally open link conductor. 20
5. A telephone system comprising telephone lines terminating in a central office, link conductors thereat for connecting said lines in pairs, at least one of said conductors being normally open, means associated with said link conductors for automatically applying ringing current to the called line upon connection of said link conductor therewith, an electromagnetic device for automatically removing the ringing current from the called line, and means associated with said link conductors and actuated after removal of the ringing current for closing said normally open link conductor. 25
- 10 15. 5. A telephone system comprising telephone lines terminating in a central office, link conductors thereat for connecting said lines in pairs, at least one of said conductors being normally open, means associated with said link conductors for automatically applying ringing current to the called line upon connection of said link conductor therewith, a relay for automatically removing the ringing current from the called line, and an electromagnetic relay associated with said link conductor and energized after removal of the ringing current for closing said normally open link conductor. 30

In witness whereof, I hereunto subscribe my name this 29 day of April, A. D., 1914. RALPH L. QUASS.
